UNITED STATES PATENT OFFICE.

DAVID W. BROWN, OF NEW YORK, N. Y.

APPARATUS FOR RECEIVING HERTZIAN WAVES.

1,319,989.

Specification of Letters Patent. Patented Oct. 28, 1919.

Application filed May 26, 1917. Serial No. 171,092.

To all whom it may concern:

Be it known that I, DAVID W. BROWN, a citizen of the United States, and a resident of the borough of Manhattan, in the city, county, and State of New York, have invented certain new and useful Improvements in Apparatus for Receiving Hertzian Waves, of which the following is a specification.

10 This invention relates to improvements in apparatus for receiving Hertzian waves.

In systems for receiving and utilizing Hertzian waves sent from distant transmitting, or oscillating, apparatus, and of which 15 systems of wireless telegraphy are examples, the energy of the high frequency electric oscillations set up by the Hertzian waves in the receiving system is so small, that, unless the effect of said oscillations upon the 20 detectors is increased, said detectors will not be properly operated by the oscillations, and consequently the distance between the sending and the receiving stations is limited.

25 It is the object of the present invention to reinforce said oscillations, or increase the effect thereof on the detectors at the receiving station, that wireless telegraphic and other systems for utilizing Hertzian 30 waves at receiving stations can be successfully and regularly operated over distances between the sending and receiving stations greater than is now practicable.

35 This invention proceeds upon the following principles: Whenever an electric current flows along a wire, there is developed a field of electro-magnetic force all around said wire. The nature of electricity remains the same in its various forms, whether of 40 constant electricity, low frequency alternating currents, or high frequency oscillating currents such as are used in wireless telegraphy. Therefore, when an independent constant current of electricity is caused 45 to flow through a field which is produced by high frequency oscillations, or when high frequency oscillations are caused to vibrate through a field which is produced by constant current electricity, then, in 50 either case, the result is an algebraic strengthening of the electrical current, either the constant current or the high frequency oscillations. By algebraic strengthening of 55 the electric current, I mean, for example, that supposing that the independent cur-

rent is positive in its direction, then the field thereby developed around the aerial will increase the strength of those vibrations of the high frequency oscillations which are in the positive direction, and will decrease the strength of those high frequency oscillations which are in the negative direction, and the effect of said oscillations will be, in the total, increased upon the detecting instruments which are exposed to the action of said high frequency oscillations. Therefore, if high frequency oscillations are caused to travel along an aerial, along which constant currents are passing and developing a field of force around said aerial, then, as said high frequency oscillations vibrate through said field of electro-magnetic force, their strength will be in some manner algebraically increased, and their effects upon detecting instruments will be greater than they would have been had not the constant current been caused to flow along the aerial on which vibrate the high frequency oscillations before reaching the detecting instruments. In this present invention I cause a continuous flow of constant current electricity to proceed along a certain part of the aerial wire which provides the path for the high frequency oscillations, when said high frequency oscillations are produced on the antenna by Hertzian waves which come from a distant sending station. This constant current, being continuous, is always flowing on the aerial, and therefore there is always produced, and is always existing a constant field of electromagnetic energy around the aerial, into which come and through which flow the high frequency oscillations. Now, as said high frequency oscillations flow through the existing and continuous field of electromagnetic energy, which is produced around the aerial, said high frequency oscillations are, in effect, magnified, or there is produced an algebraic total of the effect of both the electromagnetic energy produced by the constant current and the high frequency oscillations, and said total effect is greater upon the detecting instruments than the effect of the high frequency oscillations alone would have been. Therefore, my invention results in magnifying the effect of the high frequency oscillations beyond what their effect would have been, as received from the distant sending station if they had not been,

so to say, strengthened by the addition of the constant current electricity to the aerial.

But, as the constant current which is added to the aerial is of such strength that it would improperly affect the detecting instruments, if said constant current were permitted to reach the detecting instrument, said constant current must be prevented from reaching the detecting instrument, although said constant current must continue to flow along some part of the aerial so as to always produce the constant independent field of electromagnetic force. Now I prevent said constant current from reaching the detecting instruments and improperly affecting them when the high frequency oscillations are not coming along on the aerial, by interposing resistances which said constant current cannot pass through between the generator of said constant current and the detectors. Such a resistance to the passage of constant current is a condenser, as is well known, and I also may use a high non-inductive resistance between the generator of the constant current and said detecting instruments.

Thus this invention provides, on the one hand, for continuously supplying a current of electricity to some part of the aerial along which travel the high frequency electric oscillations on their way to the detectors, and on the other hand I interpose resistances between the generator of said constant current and the detectors, which prevent the passage of said constant currents to the detectors when the high frequency oscillations are not traveling on said aerials. When said high frequency oscillations are traveling on the aerial, the total effect of the constant current and the high frequency oscillations is some algebraic total, or some function, of the strength of both the constant current electricity and the high frequency oscillations; and said high frequency oscillations, being thus strengthened, and, as is well understood, not being prevented from reaching the detectors by the condensers or the non-inductive resistances, flow freely across the condensers, or through said non-inductive resistances, with their strength much increased over what their strength would have been had the constant current not have been caused to flow along the aerial.

The foregoing explanation will make it clear that although the detector is not in that part of the aerial which is affected by the independent constant current, yet it is operated by the high frequency oscillations, for said high frequency oscillations travel along the whole extent of the aerial, not being checked by the condenser or other high non-inductive resistances; and therefore said high frequency oscillations reach and affect the detector. Said explanation will also make it plain that the resistances, that is,

either the condenser or the high inductive resistances, do prevent the independent constant current from reaching the detector; or, as I explain it, said condenser or said high inductive resistances do "insulate" the detector from the independent constant current, so that said independent constant current does not affect the detector when the high frequency oscillations are not traveling on the aerial. But, in that case, said independent constant current simply flows round and round on its parts of the aerial which is connected with the independent generator, and through said connecting wires and generator, and continues to flow round and round in its own independent circuit while said high frequency oscillations are not being received on the aerial. When said high frequency oscillations are being received on the aerial, they flow through the field of force that has been developed around the aerial by said independent constant current, and are strengthened thereby. Said high frequency oscillations of course maintain the same frequency of vibration or alternation that they had before entering said field. The effect of said field which is produced by said constant current is to algebraically add to the strength of the high frequency oscillations, and give to said high frequency oscillations a power to influence the detector, that is greater than such high frequency oscillations, as received from the distant sending station, would have had had the independent constant current not been applied to the aerial and generated the independent field of electromagnetic force around said aerial.

The invention further contemplates that condensers may be so operatively connected with said aerials that said independent currents will normally maintain said condensers in charged condition; and said invention also contemplates the further increase of the strength of said independent field by the use of small intensifying conductive sheaths or tubes inclosing or practically inclosing said aerials, but insulated therefrom. Said sheaths or tubes may be constructed and arranged in various ways, and among them in the manner termed sometimes herein a "compound aerial", and said sheaths may either be charged or not, by electric currents independent of said high frequency oscillations.

Said detectors are represented in the accompanying drawings as coherers, but they may be of any type. Referring to said drawings, which illustrate various modifications of the invention in a diagrammatic manner, Figure 1 is a diagrammatic representation of one modification of the invention, wherein the detector is directly coupled, or closely coupled, with the aerial; Fig. 2 represents diagrammatically another modifica-

tion wherein the detector is directly coupled with the aerial; Fig. 3 is a diagrammatical representation of an inductively coupled system; Fig. 4 is a diagrammatical representation of an inductively coupled system with intensifying sheaths or tubes, and Fig. 5 is a cross section on larger scale, of a tube and aerial; Fig. 6 diagrammatically represents an inductively coupled system with a "compound aerial"; Fig. 7 is a broken elevation showing an intensifying tube composed of sections, and Fig. 8 is a broken cross section and plan showing how the aerial and tube may be supported; Fig. 9 is a cross section of a tube formed in halves.

Referring to Fig. 1, A is the antenna, and B the aerial wire preferably bare and operatively connected with said antenna. Said aerial B is electrically connected by suitable circuit wires g, g' preferably insulated, with an independent source of current electricity G, so that an electric current constantly flows along said aerial B, and constantly develops and maintains about said aerial B a field of electromagnetic energy, which field is independent of the high frequency oscillations set up on said aerial B by Hertzian waves received from the sending station. Said source of electricity G is represented in the several figures of the drawings as an electric battery, but may be any suitable generator of electricity. When such oscillations arrive on said aerial B, the effect of said independent field is, so to say, to reinforce said oscillations or increase their effect on the detector D, which is electrically connected with said aerial B, either by direct coupling, as in Fig. 1, or by inductive coupling through a transformer, as in Fig. 3 and certain other figures.

I prefer to provide choke coils k, k' in said circuit g, g' to prevent high frequency oscillations from passing along said wires g, g' , and I also prefer to provide a variable resistance R to regulate the strength of the independent current delivered to said aerial B. If it is desired to utilize said aerial B, both for sending and for receiving oscillations, a switch S of any suitable design may be provided; said switch S being indicated in Fig. 1 and other figures in the position for receiving oscillations from the antenna, and o indicating a contact and circuit for placing the oscillator, not shown, in circuit with said aerial, the detector and other apparatus of the local receiving circuit being then cut out.

To electrically separate or insulate the current supplied to said aerial B from, and prevent its improperly affecting the detector, (for said current is so strong, as above stated, that it would otherwise improperly operate the detector), I provide suitable separating or insulating devices, preferably a variable condenser C between said detector

D and said aerial B, and the independent current supplied to said aerial B will preferably be a constant current.

The operation of the system set forth in Fig. 1, of the drawings is as follows: Assume that there are no Hertzian waves coming from the distant station, there will then, nevertheless, be a continuous current from the independent generator G flowing along the aerial B-B and in the circuit $g-g'$. This current will generate a field of electro-magnetic force around said aerial B-B in that part of the said aerial which is between the connections of the wires $g-g'$ with said aerial. This current will, however, not be able to reach or injuriously affect the detector D, because of the condenser C, or other suitable resistance, which said constant current cannot traverse. Said constant current will, therefore, flow round and round in its independent circuit, being regulated by the variable resistance R, and being able to traverse the choke coils k , which practically interpose no resistance to the flow of the constant current. Thus the condition now is, that there is now constantly maintained a field of electro-magnetic force immediately around that part of the aerial B-B through which said constant current is flowing; but this force cannot affect the detector. Now suppose that Hertzian waves arrive on the antenna A from the distant sending station. Those Hertzian waves set up a high frequency oscillation on the antenna, which high frequency oscillations readily pass through the condenser A' and flow along said aerial B-B, and through said condenser C to the detector. It will be seen that these high frequency oscillations have to pass through the constantly maintained field of electro-magnetic force on their way from the antenna A to the detector D. Now as said high frequency oscillations pass through said constantly maintained field, (which is around the said aerial B-B that forms the path for said high frequency oscillations), they absorb, as it were, energy from said constantly maintained field, and are, so to say, revivified, so that they act on the detector more energetically than they would have done had they not been so revivified.

I may arrange the condenser C in series with the aerial B and the independent circuit wire g , as indicated in Fig. 2, so that said condenser will be charged inductively up to the point at which the counter electromotive force of said condenser equals the electromotive force of said independent current. As said condenser C is in series with the generator G, then, as is well understood, the said constant generator circuit will become charged up to that limit at which the counter-electro-motive force of said condenser C becomes as great as the electro-

1
motive force of the current from said generator G. Then, provided no high frequency oscillations are traveling on said aerial B—B, there will be on said aerial an electric potential equal to that of said counter electro-motive force. Now, when the high frequency electric oscillations pass along through said field and through the condensers C—C' on their way to the detector D, 5 the passage of said high frequency electric oscillations through the said condensers will induce the flow also of some or more of the electro-motive force that was, so to say, stored on said aerial B—B', and said flow 10 will tend to increase the effect of said high frequency electric oscillations on said detector as long as said high frequency electric oscillations flow through said condensers and induce the discharge across them of some or 15 more of said accumulative electric motive force. In this arrangement of apparatus I prefer to place a second condenser C', or other suitable insulating device, between said condenser C and the detector, and to 20 connect the wire g' with the aerial wire B at a point between said condensers C—C'.

Referring to Fig. 3, which shows the detector D inductively coupled with said aerial B through a transformer T—T', a 25 condenser C, preferably variable, is now operatively connected with said aerial B between the connection with said circuit wire g' and the transformer T—T'. The operation of this form of the invention will 30 be readily understood from the foregoing description of the construction and operation of the apparatus of Fig. 1.

Referring to Figs. 4 and 5, and noting that intensifying sheaths or tubes H, which 35 are more specifically the subject of my other application for United States Letters Patent, granted August 7, 1917, No. 1,235,650, may be applied as well to a direct coupled as to an inductively coupled 40 system, H is a small metallic tube, preferably of copper, inclosing or substantially inclosing, as great a length as is practicable of said aerial B, but insulated from said aerial. The diameter of said tube H should 45 be the smallest practicable to allow for adequate insulation from said aerial B. Said insulating material may be of any suitable kind, and I prefer insulating disks h, h, Fig. 5, secured at such intervals in said tube H 50 as to prevent all contact of said aerial B with said tube H, said aerial passing axially through said disks. I also prefer to provide openings through said disks, as notches in the edges, to permit circulation of air to 55 diminish the tendency of said tube H to heat. An insulating cap, as j, may be placed over the upper end of said tube H to keep out moisture. Such small conductive tubes, 60 which I sometimes term "intensifiers", or 65 "intensifying tubes", exercise an influence to

intensify any oscillations vibrating on said aerial B; and I may further increase this effect by connecting said tube H by insulated wires l—l', with an independent electric current (preferably a constant current) 70 from any suitable generator of electricity, so that an electric current continually flows along said tube H; but said tube H may be used without such current.

The generator of the current for said 71 tube H, if current is supplied to said tube, may be either a separate generator G', as indicated in Fig. 4, or may be the same generator which supplies independent current to said aerial B; and I prefer to so arrange 8 the circuit wire connections with said tube H, that the direction of current along said tube H will be the same as that along said aerial B. I also prefer to provide choke coils k—k', at proper positions to prevent 8 the high frequency oscillations from reaching said tube H (see Figs. 4 and 5); and when said tube H is connected with a separator generator G' (Fig. 4) I also prefer to provide a separate variable resistance R'. 9

The operation of this form of the invention will be readily understood with but little further explanation. Assuming that the independent current with which said tube H is charged is flowing in the same direction 9 as the independent current on said aerial B—B, then the combined effect of the parallel currents, which are flowing both on said aerial B—B, and in said tube H, will be to generate a strong field of electro-magnetic force within said tube H and around said aerial B—B. Now, when Hertzian waves arrive on the antenna A, and high frequency oscillations travel on said aerial B—B, the effect of said high frequency oscillations on said detector D will be correspondingly increased.

In Figs 4 and 5 said intensifier sheath is shown as a small tube H, inclosing the aerial wire B, but these intensifier sheaths may be 1 also constructed as coils of insulated wire P, coiled around said aerial B, the whole forming what I term a "compound aerial", and as indicated in Fig. 6. When such a "compound aerial" is used, I prefer to connect the ends of said coil P with their own independent electric generator G', and with choke coils k—k' and variable resistance R', though, of course, said coil P might be connected with the same generator G as 1 supplies the independent current to said aerial B. Said coil P will surround as great a length of aerial B as is practicable, and will act as an intensifying sheath, the compound aerial being of convenient construction for transportation and erection at any station. The operation of the apparatus will be plain from the foregoing explanations.

Said intensifier tubes may be made in sec- 1

tional lengths H' , placed end to end and around the aerial wire, which may also be in pieces B' joined together at the ends by electrically conductive couplings X , (Fig. 7). To insure good insulation of said tubes H' from said wires B' at points adjacent to said couplings X , insulating disks h^2 are placed around said wires B' between the ends of said couplings X and said tube sections H' ; and it is also advisable to place other insulating disks h inside of and adjacent to each end of said tube sections H' . The ends of adjacent tube sections H' are electrically connected by conductive sleeves 15 or strips V , secured to the adjacent ends of said tube sections. The said insulating disks h and h^2 may be very conveniently constructed by winding adhesive non-conducting tape, of any suitable width, around 20 the said aerial wire B or B' , at desired points, so as to form plugs or disks of a size to fit within said tubes B or B' ; the adhesiveness of the tape cementing it sufficiently firmly to said aerial wire, and also 25 holding the successive windings of the tape together. In this way the aerial, with its tube, may be readily assembled at the site where the aerial is to be erected.

To facilitate supporting the aerial and its 30 tube on the aerial supporting frames or masts, the said sections H' of said tube may be provided with supporting shoulders n . Certain of said shoulders n rest on insulating blocks or straps y which are fastened to 35 the supporting frame W , as indicated in Fig. 7. A cross sectional view of said strap y , and of the sheath and the insulating disks is indicated in Fig. 8.

The said intensifier tubes may in some 40 cases be conveniently formed in halves, with longitudinal flanges to secure the halves together around the aerial wire B or B' , as indicated in Fig. 9, and the insulating disks may also be formed in halves 45 h^3 and secured in any suitable manner in said half tubes H' .

It will be understood that the usual instruments, such as relay telephone or other instruments, will be provided in the local 50 circuit of the detector, which local circuit is indicated in Figs. 1, 2, 3, 4 and 6 by the wires $t-t'$.

It will be well to place a condenser A' between the antenna A and the connection of 55 the independent circuit wire g with said aerial B , as indicated in Fig. 1 and certain other figures, to diminish possible leakage

of the independent current from said antenna tips.

When plugs of adhesive non-conducting 60 tape are used, as hereinbefore suggested, said plugs may have a loose fit in the intensifier tubes H or H' , so as to permit of circulation of air in said tubes if desired. Said caps j may also be located so as to 65 leave an annular aperture between the said caps and the upper ends of said intensifier tubes for the same purpose.

Now having described my improvements I claim as my invention. 70

1. In a system for receiving high frequency electric oscillations, the combination of an aerial, a detector in operative connection with said aerial, means for continuously maintaining an electric current on said 75 aerial of greater strength than sufficient to operate said detector and means normally insulating said current from said detector.

2. In a system for receiving high frequency oscillations, the combination of an 80 aerial, a detector operatively connected with said aerial, means for continuously maintaining an electric current on said aerial of greater strength than sufficient to operate said detector, and a condenser between 85 said detector and the connection of said current with said aerial.

3. The combination in a system for receiving high frequency electric oscillations, 90 of an aerial, a detector operatively connected therewith, an independent generator of current of more than sufficient strength to operate said detector, a circuit connecting said current with said aerial, a condenser to prevent said current reaching said detector, and choke coils preventing high frequency oscillations from passing into said 95 circuit.

4. The combination in a system for receiving high frequency electric oscillations 100 of a receiving aerial, a shunt circuit connected therewith, and an independent electric generator in said shunt circuit adapted to continuously maintain a current in said shunt circuit and a part of the aerial, and 105 choke coils and a variable resistance in said shunt circuit.

Signed at New York city, in the county of New York, and State of New York, this 25th day of May, A. D. 1917.

DAVID W. BROWN.
